INVENTORS

UNITED STATES PATENT OFFICE.

JOHN FRANCIS BOORAEM, OF GREENWICH, CONNECTICUT, AND GABRIEL E. ROHMER, OF WOODSIDE, NEW YORK, ASSIGNEES TO THE BOORAEM & ROHMER PATENT COMPANY, A CORPORATION OF NEW YORK.

EXPANSION-BOLT.

1,120,368.

Specification of Letters Patent.

Patented Dec. 8, 1914.

Application filed November 27, 1911. Serial No. 682,675.

To all whom it may concern:

Be it known that we, JOHN FRANCIS BOORAEM, a citizen of the United States of America, and residing in Greenwich, in the county of Fairfield and State of Connecticut, and GABRIEL E. ROHMER, a citizen of the United States of America, and residing in Woodside, in the county of Queens and State of New York, have invented certain new and useful Improvements in Expansion-Bolts, of which the following is a specification.

This invention relates to expansion bolts and has for its object to provide a new bolt which may be readily applied to structural uses.

An embodiment of the invention is shown in the drawings annexed, and will be described in detail hereinafter and finally 20 pointed out in the claims.

In the accompanying drawings, Figure 1 shows a side view with part broken away to show a section of our improved expandable member, Fig. 2 is a bottom view of the same 25 showing the slot which enables the expandible member to expand and press against the walls of the hole to which the expansion bolt is applied, Fig. 3 is a vertical, central section of the expanding member, Fig. 4 is 30 a top view of the same, Fig. 5 shows a form with an interior screw-thread, Fig. 6 shows the expanding member and expandible member applied to a bolt, Fig. 7 is a modified form of a bolt shown in Fig. 6 in which two 35 expandible members are arranged back to back, in which one expanding member is screw-threaded and the other is not screw-threaded, Fig. 8 is a modified form of the bolt shown in Fig. 7, which shows a stud 40 bolt, Fig. 9 is a modified form of expandible member showing the two back to back members in Figs. 7 and 8, integral with each other, Fig. 10 is a modified form of the expandible member shown in Fig. 9, Fig. 11 is 45 another modified form of expandible member, and Fig. 12 shows the application of the bolt to the hole.

Similar letters of reference indicate corresponding parts throughout the several figures of the drawings.

Referring to the drawings and more particularly to Fig. 12, the hole is formed into concrete 15, the walls 16 of which are engaged by the exterior part of the expandible

member 17. The expandible member 17 is 55 engaged at its interior by the expanding members 18, which are of substantially conical shape and engaged at either side of the expandible member, the smallest diameter of the expanding member being substantially 60 equal to the largest diameter of the expandible member. By the continued penetration of the conical members, the expandible members are expanded and forced against the walls of the hole, the increased penetration 65 of the conical expanding members increasing the tightness of the hold. For this purpose the expandible member is provided with a slot 19 longitudinally along the expandible member, and this slot permits the expandible 70 member to be expanded or extended. The expanding members 18 are supported by the bolt 20 which is provided with a nut 21. One of the expanding members 18 and that 75 farther from the nut 21 is interiorly screw-threaded as shown in Fig. 6, and by the continued rotation of the nuts 21, the expanding member enters the expandible member.

The slot 19 is clearly shown in Fig. 2. In the embodiment shown in Fig. 6, just 80 one expanding member 18 and one expandible member 17 with one nut 21 and one bolt 20 are shown. By the rotation of the nut 21, the expanding member enters the expandible member 17 and thereby the expandible member is extended. It will be noted 85 that in the embodiments shown, the inner surface of the expandible member and the outer surface of the expanding member are inclined in the same direction to the bolt, 90 the inclination of said outer surface of the expanding member being greater than the inclination of said inner surface of the expandible member.

In the embodiment shown in Fig. 7 the expandible members 17^a and 17^b are arranged 95 back to back and have a conical interior which is adapted to be engaged by the expanding members 18^a and 18^b while the nut 21 is provided to operate the parts.

In Fig. 8, the bolt 20 is provided with a bolt head 31 while the jam-nut 22 holds the parts in position and enables the same to be tightened up when the parts are loosened by vibration.

In Fig. 9 the expandible members 17^a and 17^b shown in Figs. 7 and 8 are made integral with each other and form one ex-

pansible member which has its exterior tapering so as to come to a peripheral meeting edge 24.

In the embodiment shown in Fig. 10, the exterior of the expansible member is cylindrical as shown at 23 instead of in the tapering form as shown in Fig. 9.

In the embodiment shown in Fig. 11, the parts are again divided into two parts back to back and are arranged with a cylindrical exterior line.

In the embodiment shown in Fig. 12 the longitudinal slots is arranged V-shaped or tapering from the ends of the expansible members to the meeting edges of the same, resulting from the expansion of the yieldable expansible member.

The expansible member is made of a suitable elastic metal and the expanding member is also made of suitable steel or malleable iron. The expansible member retains its shape in substance but is expanded by the interior radial pressure exerted by the entrance of the conical expanding member.

It will be noted that the male members in Fig. 12 enter the female or expansible members very deeply, and have their approximate ends almost contiguous to each other.

We have shown several embodiments of our invention, but changes may be made therein without departing from the spirit of the invention, as defined in the appended claims.

Having thus described our invention, we claim as new and desire to secure by Letters Patent:

1. In an expansion bolt, a bolt, an expansible member of springy material, an expanding member, the inner surface of

said expansible member and the outer surface of said expanding member being inclined in the same direction to the bolt, the inclination of said outer surface of the expanding member being greater than the inclination of said inner surface of the expansible member, the outer surface of said expansible member being inclined to the bolt in an opposite direction to the inner surface thereof.

2. In an expansion bolt, a bolt, an expansible member of springy material, an expanding member, the inner surface of said expanding member and the outer surface of said expanding member being inclined in the same direction to the bolt, the inclination of said outer surface of the expanding member being greater than the inclination of said inner surface of the expansible member.

3. In an expansion bolt, a bolt, an expansible member of springy material, an expanding member, said expansible member having a longitudinal slot, the outer surface of said expanding member and the inner surface of said expansible member being inclined in the same direction to the bolt, said outer surface of the expanding member having a greater inclination than said inner surface of the expansible member, the longitudinal slot of the expansible member extending through the length thereof.

In testimony, that we claim the foregoing as our invention, we have signed our names in presence of two subscribing witnesses.

J. FRANCIS BOORAEM.
GABRIEL E. ROHMER.
